UNITED STATES PATENT OFFICE.

ANDREW J. BRYAN, OF GRAHAM, TEXAS.

COTTON-BOLL THRESHER.

1,182,343.

Specification of Letters Patent.

Patented May 9, 1916.

Application filed May 20, 1913. Serial No. 768,763.

To all whom it may concern:

Be it known that I, ANDREW J. BRYAN, a citizen of the United States, residing at Graham, in the county of Young and State 5 of Texas, have invented certain new and useful Improvements in Cotton-Boll Threshers, of which the following is a specification.

This invention relates to new and useful 10 improvements in cotton boll threshers.

The object of the invention is to provide a device into which unopened and partially 15 opened bolls may be fed and the bolls bursted and the cotton separated therefrom.

Another feature resides in means for 15 cleaning the cotton and also means for regulating the passage of the cotton through the thresher.

A still further object of the invention 20 is to provide a device of the character described that will be strong, durable, efficient, and simple and comparatively inexpensive to construct, also one in which the several parts will not be likely to get out 25 of working order.

With the above and other objects in view the invention has relation to certain novel 30 features of construction and operation, an example of which is described in the following specification and illustrated in the accompanying drawing, wherein:

Figure 1 is a plan view of the thresher, Fig. 2 is a longitudinal sectional view on the line $x-x$ of Fig. 1, Fig. 3 is a transverse sectional view on the line $a-a$ of Fig. 35 2, Fig. 4 is a partial end elevation, the door being omitted, Fig. 5 is a detail in section on the line $y-y$ of Fig. 4, and Fig. 6 is a detail of the adjusting device.

In the drawings the numeral 1 designates 40 side walls of a casing. A metal top plate 2 is secured to the side walls. A bottom plate 3, a curved door 4, and a board 5 form the bottom of the casing. The top and bottom of the casing are curved as shown in Fig. 2 whereby an elongated central portion is formed for the reception of a drum 6 fixed on a shaft 7 mounted in the side walls 1. One end of the shaft projects exteriorly and a driving pulley 8 is fixed 45 thereon.

The bottom 3 is curved downward and the door 4 has its lower end hinged thereto, a pocket thus being formed. The upper end 50 of the door is suitably fastened to the board 5. A breast 9 is hinged adjacent the drum

6 by means of depending arms 10 hinged at their lower ends to the walls 1. The drum has radial pins 11 and the breast has similar pins 12 between which the pins 11 55 pass in staggered relation. Cotton bolls and cotton from the field is fed into the casing over the board 5 to the drum 6 which revolves in a counter-clockwise direction (Fig. 2). The bolls and cotton are carried down between the pins 12 by the pins 11 whereby the bolls are bursted and the cotton removed.

A blast of air carries the cotton into the casing over the board 5 and after the hulls 70 and foreign matter has dropped onto the door and the bottom plate, the same blast of air carries the cotton out through the contracted ends of the plates 2 and 3 to a delivery spout 14. Any cotton which may 75 adhere to the drum and its pins 11 will be removed by guard pins 15 depending from a bar 16 over the drum and between which the pins 11 pass. This guard prevents the cotton being carried back to the breast. 80

A baffle plate 17 is hinged to the bar 16 and extends transversely of the casing to the side walls 1 and longitudinally to the entrance. This baffle plate is perforated and has its free end adjustably supported 85 by a toothed bar 18 engaging in a slot 19 in the board 5. The cotton is drawn in between the board and the baffle plate and by regulating the space therebetween the feed of the cotton may be controlled. 90

The upper end of the breast 9 has brackets 20 mounted on its outer side and eccentrics 21 are rotatably confined in these brackets. The eccentrics are fixed on a slot 22 mounted in the walls 1 and having a crank handle 23 on one end which engages a segmental rack 24 mounted on the outside of one of the walls 1. By swinging the handle 23 the eccentrics are rotated and the breast adjusted toward and from the cylinder, and thus the cotton according to its condition, is permitted to pass any tendency toward "choking" being avoided. The cotton in passing between 11 and 12 will be more or less cleaned and all unopened bolls will be bursted and the cotton removed. Should in running cotton through the thresher, we come to portions which did not necessarily need cleaning, the baffle plate 17 could be dropped upon the board 100 and this portion of the cotton quickly passed through the machine. 110

What I claim is:

1. In a device of the character described, a pneumatic flue, a baffle plate separating said flue into two compartments, a toothed cylinder rotatably mounted in one of the said compartments, a breast coacting with said cylinder, and a bar carried by the baffle plate, said bar having guard pins co-operating with the toothed cylinder.
- 10 2. In a device of the character described, a pneumatic flue, a baffle plate separating said flue into two compartments, a toothed cylinder rotatably mounted in one of the said compartments, a breast coacting with

said cylinder, and a bar carried by the baffle plate, said bar having guard pins co-operating with the toothed cylinder, in combination with means for adjusting said baffle plate in said flue to thereby increase or decrease the area of the compartment wherein 20 said toothed cylinder is located.

In testimony whereof I have signed my name to this specification in the presence of two subscribing witnesses.

ANDREW J. BRYAN.
